United States Patent Office

Des. 211,781
Patented July 30, 1968

211,781

BUILDING

Vaughn L. Shamburg, Topeka, Kans., assignor to Lil' Duffer of America, Inc., Topeka, Kans., a corporation of Kansas

Filed Aug. 21, 1967, Ser. No. 8,335

Term of patent 14 years

(Cl. D13—1)

Fig. 1.

Fig. 2.

Fig. 3.

FIG. 1 is a front perspective view of the building;

FIG. 2 is a rear perspective; and

FIG. 3 is a side perspective of the building.

The side opposite to that shown in FIG. 3 is the same in appearance as that shown in FIG. 3.

I claim:

The ornamental design for a building, as shown and described.
